UNITED STATES PATENT OFFICE

2,398,431

STOKER

George A. Kohout, Chicago, Ill.

Application October 7, 1943, Serial No. 505,288

7 Claims. (Cl. 110—104)

The present invention relates to stokers and is particularly concerned with the provision of a stoker unit which is portable and which is adapted to be applied to any existing furnace by the simple expedient of providing an opening a short distance above the grate over the fire and moving the stoker unit into position with its discharge end extending into the furnace opening.

It is the principal purpose of this invention to provide a stoker of the general character above described by which ordinary coal varying in size, wet or dry, may be advanced from a hopper to an air blast duct and forced by an air blast through the duct into the furnace and spread in such fashion as to substantially uniformly cover the grate. I am aware of course that many stokers have been made wherein the fuel is forced into the furnace by an air or steam blast and distributed by the force of the blast within the furnace. My prior Patents Nos. 2,178,360 and 2,257,693 illustrate one type of stoker of this character. The stoker of the present invention is particularly advantageous in handling wet coal. Furthermore, it has the advantage that if the coal contains particles that are too large it will separate these large particles and return them to the hopper until they become broken up to a size that will be handled readily by the air blast.

The invention contemplates a portable stoker of the character described wherein the air blast conduit through which the coal is advanced into the furnace may be heated by the furnace gases to any desired degree whereby to facilitate the handling of wet coal and to prevent it from sticking in the air blast conduit. The invention contemplates also deflecting devices associated with the air blast conduit whereby to control the spread of the fuel over the furnace grate and prevent the air blast from blowing the fuel over the bridge wall in the furnace.

More particularly it is a purpose of the present invention to provide a portable stoker with a variable feed that is capable of being applied to any existing furnace installation and that will feed the coal reliably through a wide range of rates regardless of whether the coal is dry or wet.

The features and advantages of the invention will appear more fully as the description proceeds in connection with the accompanying drawings wherein a preferred form of the invention is shown. It should be understood however that the drawings and description are illustrative only and are not to be taken as limiting the invention except insofar as it is limited by the claims.

In the drawings:

Figure 1 is a longitudinal sectional view taken through a furnace showing my improved stoker connected thereto for supplying fuel to the combustion chamber of the furnace;

5 Figure 2 is a longitudinal sectional view taken through the stoker and showing it in feeding position;

Figure 3 is a plan sectional view taken on the line 3—3 of Figure 2;

10 Figure 4 is a plan sectional view taken on the line 4—4 of Figure 2;

Figure 5 is a view in side elevation of the fuel feeding duct casting of the stoker, this view being taken to show the side opposite that shown in Figure 2;

15 Figure 6 is a sectional view taken on the line 6—6 of Figure 2; and

Figure 7 is an enlarged sectional view taken on the line 7—7 of Figure 2.

20 Referring now in detail to the drawings, the furnace shown diagrammatically in Figure 1 has a front wall 10, a bridge wall 11 and a combustion chamber 12 in which a grate 13 is mounted. The front wall is shown as provided with an opening 14 below the level of the grate which is closed by a door 15. The front wall also has an opening 16 above the grate and substantially on the level therewith, this opening being closed by a door 17. The opening 14 is of course to permit access

25 beneath the grate to the ash chamber, while the opening 16 permits direct access to the top of the grate for cleaning it. The furnace also is provided with a third opening 18 above the opening 16, which opening is the fuel feed opening through which coal is blown and spread over the grate 13.

30 My invention comprises a stoker 20 including a hopper 21 that is tilted at an angle of substantially 45 degrees to the horizontal. The hopper has side walls 22 and 23 that converge forwardly and a bottom wall 24 on which a feed screw 25 is located. The back end of the hopper is closed by a plate 26 and the side and end wall extensions 27, 28 and 29 are provided to increase the capacity of the hopper itself.

35 A tubular fuel feeding casting 30 extends into the opening 18. This casting is provided with a small hopper 31 that extends from an opening 32 in the top of the casting to an opening 33 in the bottom wall 24 of the hopper near its upper end. The opening 33 is covered by a perforated part 34 of a feed screw housing 115, the perforations 35 in this part being of such a size as to pass coal up to the sizes it is desired to have enter the furnace through the casting 30. The casting 40 30 consists of an upper hollow portion 36 and

a lower hollow portion 37 separated by a web 38. The upper hollow portion 36 is the duct through which the fuel enters the furnace from the small hopper 31 while the lower hollow portion 37 is a duct for hot gases from the furnace for heating the web 38 and thereby the upper duct to prevent wet coal from clogging.

The hopper 21 and the fuel feeding casting 30 are supported upon a framework which is made up of a rear extension 40 of the bottom wall 24 of the hopper. This plate extension 40 has brackets 41 thereon which extend downwardly and provide means for mounting the plate on a shaft 42 on which is journaled two supporting wheels 43 and 44. The plate 40 supports a motor 45 which may be variable in speed or which may be connected by variable speed mechanism indicated generally at 46 and 47 to a shaft 48 on the feed screw 25. Any suitable variable speed mechanism is sufficient for connecting the shaft 48 to the motor 45 so as to give a wide range of speeds to the feed screw.

The plate 40 is connected by two channel irons 49 to a front post 50 which is telescoped with another post 51 that is mounted on a small wheel 52. A clamp 53 is provided on the post 51 so as to determine the height of the post 50. It will be evident that by releasing the clamp and setting it lower or higher on the post 51 the post 50 and the parts supported thereby can be changed in elevation. The post 50 carries a plate 54 at the top thereof which supports the casting 30, the casting having suitable flanges 55 bolted to the plate 54. The plate 54 desirably is cut out to receive a pipe 56 that extends downwardly from the casting. The pipe 56 has swiveled on its lower end a hollow T 57 and the T 57 carries a pipe extension 58 and an enlarged discharge bell 59. An opening 56a is cut in the wall of the pipe 56. The lower end of the pipe 56 is closed by a plug 56b.

The channel irons 49 serve to support a plate 60 which is the base of a fan 61. The fan 61 preferably is of the centrifugal type and has its discharge end 62 extending upwardly into the rear end of the upper duct 36 of the casting 30. The inlet of the fan is in the side thereof facing the bell 59 and the bell is held in adjusted position with respect to the inlet 63 by an adjustable stop screw 64 that is threaded into an ear 65 provided on the bell 59. A spring 66 having one end connected to the bell and the other end connected to the fan housing urges the bell toward the fan housing so that by adjusting the stop screw 64 the distance between the bell and the fan inlet can be varied. The fan is driven by a motor 67 which is mounted on the base plate 60.

The rear end of the air duct 36 has a damper 68 pivoted therein on a cross shaft 69. The rear of the casting 30 turns downwardly, a small plate 70 being provided at the lower end of the casting to fit around the outlet 62 of the fan. The damper 68 being back of the inlet 32 for the coal limits the amount of air that will be delivered from the fan against the coal falling from the inlet 32. The shaft 69 is journaled in the casting 30 and extends outwardly through the casting (see Figure 5) and through a bracket 71 where it is provided with a lever 72. The lever 72 can be adjusted to vary the position of the damper 68 and it can be locked in position by a lock pin 73 which rides in a slot 74 of the bracket 71.

Referring now to the air duct 36 and the hot gas duct 37, it will be noted from an examination of Figures 4 and 6 that the air duct 36 is sub-

stantially unobstructed from the inlet 32 to a point at 75 where it expands laterally and is divided into two channels by an adjustable vane 76. This adjustable vane is keyed to a pin 77 that is journaled in the casting 30 and extends upwardly above it. The pin 77 (see Figures 3 and 5) is fixed to a link 78 which in turn is pivoted to a bell crank lever 79 that has a slot 80 in which a pin 81 of the link 78 rides. The bell crank lever is pivoted on the casting 30 by a pin 82 and is connected to a manually adjustable link 83 which has a handle 84 thereon. This link 83 is screw threaded and has two nuts 85 and 86 thereon spaced apart so as to receive a lug 87 therebetween. The lug 87 is slotted to receive the link 83. In normal operation the vane 76 is originally adjusted by setting the nuts 85 and 86 so as to divide the coal between the two diverging channels in such fashion as to give the proper distribution in the furnace. When it is desired to cut off the discharge from one side or the other of the furnace the operator lifts the link 83 by means of the handle 84 and then by pushing or pulling on the link 83 he can turn the vane 76 so as to close one of the discharge channels and direct all of the fuel through the other one.

The operator, by directing all of the fuel to one side of the furnace, can burn out the fuel on the other side and clean the grate and then spread the fire over both sides of the grate. He doesn't have to put out the fire to clean the grate.

The hot gas inlet conduit 37 (see Figures 2 and 6) has downwardly directed elongated openings 88 at the front end of the casting. Between the openings there are a series of webs 89 that extend across the passage in the conduit 37. Likewise throughout the length of the conduit 37 there are a plurality of posts 90 connecting the bottom wall of the conduit with the web 38 so as to provide ample means to deflect the hot gases and to transmit heat from the gases to the web 38. At its rear end the duct 37 is curved around a web 37a so as to baffle the hot gases directly beneath the coal inlet 32 and insure adequate heating of the coal receiving part of the casting 30. The duct 37 opens downwardly into the tube 56. When the bell 59 is over the inlet 63 of the fan it will be obvious that the fan suction will draw hot gases through the inlet openings 88 and through the duct 37, then down through the tube 56 and the bell 59 to the fan. The suction in the duct 37 will be governed by the spacing between the fan inlet and the bell 59. By adjusting the bell 59 by means of the stop screw 64 the rate of flow of the hot gases can be regulated and the heating of the casting 30 can be controlled.

Owing to the fact that the direct heat from the grate upwardly toward the inlet openings 88 and the flow of hot gases to these openings would tend to burn out the front end of the duct 37 I provide means for protecting the inlet openings 88 in the front end of the duct 37. This means comprises a hollow casting 91 (see Figures 2, 6 and 7). The hollow casting 91 has an opening 92 by which the gases may pass to the openings 88. This casting is supported by a pair of ears 93 and 94 on the casting 30 and by inturned lips 95 and 96 on the hollow casting 91.

The discharge ends 36a and 36b of the conduit 36 are rounded as indicated at 97 and 98 (see Figure 7) so as to tend to deflect the fuel outwardly and downwardly at the front of the furnace. This deflection however is not sufficient to take care of the particles that shoot straight out

and might be thrown over the bridge wall of the furnace in those cases where it is necessary to use a fairly heavy blast to handle the discharge of the coal through the conduit 36. In order to prevent the difficulty of having the coal blown over the bridge wall, and furthermore, in order to protect the discharge ends 36a and 36b of the conduit 36 I provide a shielding casting 99 which extends forwardly and downwardly over the discharge openings 36a and 36b. This casting is notched as indicated at 100 to receive two ribs 101 and 102 that are provided on the top of the casting 30 at its forward end, the ribs serving as a pivot on which the casting 99 may rock. The casting 99 has a rearwardly extending arm 103 by which it can be adjusted. This arm is extended underneath the long arm 104 of a bell crank 105, the short arm 106 of which extends upwardly alongside of the casting 30 in front of a lug 107. An adjusting screw 108 is threaded through the lug 107 and by turning this screw the bell crank lever 105 can be rocked on its pivot to raise and lower the end 104 thereof. Obviously if the end 104 is depressed the free end of the casting 99 is lifted due to the pressure of the end 104 on the arm 103. Likewise if it is desired to lower the free end of the casting 99 the arm 104 is raised.

In order to inspect the conduit 36 immediately adjacent the inlet 32 I provide an opening 109 in the side of the casting 30. This opening is closed by a movable plate 110. Of course when it is desired to clean the interior of the conduit 36 this can be done by simply removing the stoker from the furnace so that access may be had through the discharge channels 36a and 36b.

Any suitable means may be provided for fastening the stoker in position once it has been brought up to a furnace. For this purpose I have shown a bracket 111 (see Figure 2) pivoted on the post 50 and provided with an adjustable link 112. On the end of the link 112 I provide a hook 113 and any suitable pin 114 can be fastened to the furnace front to receive the hook 113.

The arrangement of the feed screw 25 so as to feed coal upwardly to the perforations 35 and thus permit the coal to work through these perforations also enables me to prevent large particles of coal from getting into the conduit 36 and clogging it. The housing 115 encloses the upper portion of the screw 25 but this housing is open at its upper end so that any coal which does not pass through the perforations 35 will simply be fed out of the upper end of the housing and will fall back into the lower part of the hopper. An agitator wheel 116 of a well known design has gear teeth 117 thereon engaging with the feed screw 25 to turn the agitator wheel. This agitator wheel is journaled upon a shaft 118 that extends transversely of the hopper, the wheel being positioned by pipe sections 119 interposed between the hub of the wheel and the sides of the hopper.

In order to move the coal inwardly from the sides of the hopper to the feed screw I secure the pipe sections 119 to the hub of the sprocket wheel 116. I mount on the pipe sections two discs 120 and 121 which have wedge shaped lugs 122 and 123 thereon arranged to push the coal toward the feed screw as the discs rotate. The discs are fixed to the pipe sections 119 which are welded to the hub of the sprocket agitator wheel 116. The discs therefore rotate in unison with the sprocket wheel. The sprocket wheel has pins 124 thereon to agitate the coal.

The feed screw housing 115 is held in place on the bottom of the hopper by two angle irons 125

and 126 (Fig. 3) which are fastened to the hopper bottom 24. The housing is cut away as shown in Figure 2 at the height indicated at 127 to allow coal to feed into the screw from the sides. In order to fill in the bottom of the hopper on opposite sides of the cut away housing up to the level indicated at 127 I employ floor boards (not shown) and bevel the upper edges so that the coal will not lodge at that point. The lower part of the hopper floor is desirably provided with drain openings 128 so that water from wet coal can drain out.

The shielding casting 99 is so shaped on its lower or coal engaging surface as to direct and spread the coal according to the needs of the installation. A plane surface as shown or a surface of any other desired nature may be used. The casting acts to spread the coal laterally as well as to deflect it downwardly.

From the foregoing description it is believed that the nature and advantages of the present invention will be readily apparent to those skilled in this art.

Having thus described my invention, what I claim as new and desired to secure by Letters Patent is:

1. A stoker of the character described, comprising a fuel feeding duct, a fan having its outlet connected to said duct whereby to supply a fluid blast to advance coal through said duct, a coal inlet to said duct, said duct having means at its outlet end to spread coal laterally as it is blown from the duct, a damper in said duct between the fan inlet to the duct and the coal inlet to the duct for controlling the fluid blast and thereby varying the distance to which the coal is blown from said duct, a second duct contiguous to and having a common wall with the coal feeding duct, said second duct having an inlet at the coal discharge end of the coal feeding duct, and means for connecting the suction side of said fan to the second duct whereby to cause the fan to draw gases through the second duct, from the area adjacent to the discharge end of the fuel feeding duct.

2. A stoker of the character described, comprising a fuel feeding duct, a fan having its outlet connected to said duct whereby to supply a fluid blast to advance coal through said duct, a coal inlet to said duct, said duct having means at its outlet end to spread coal laterally as it is blown from the duct, a second duct contiguous to and having a common wall with the coal feeding duct, said second duct having a hot gas inlet at the coal discharge end of the coal feeding duct, and means for connecting the suction side of said fan to the hot gas duct whereby to cause the fan to draw hot gases through the hot gas duct, said second duct having a baffle chamber directly beneath the coal inlet to said first duct for increasing heat transfer to the first duct at the coal inlet.

3. A stoker of the character described, comprising a fuel feeding duct, a fan having its outlet connected to said duct whereby to supply a fluid blast to advance coal through said duct, a coal inlet to said duct, said duct having means at its outlet end to spread coal laterally as it is blown from the duct, a second duct contiguous to and having a common wall with the coal feeding duct, said second duct having a hot gas inlet at the coal discharge end of the coal feeding duct, and means for connecting the suction side of said fan to the hot gas duct whereby to cause the fan to draw hot gases through the hot gas duct, said

connecting means including means to vary the suction effect of the fan on the hot gas duct and thereby vary the rate of drawing hot gases through said duct.

4. A stoker of the character described, comprising a fuel feeding duct, a fan having its outlet connected to said duct whereby to supply a fluid blast to advance coal through said duct, a coal inlet to said duct, said duct having means at its outlet end to spread coal laterally as it is blown from the duct, a second duct contiguous to and having a common wall with the coal feeding duct, said second duct having a hot gas inlet at the coal discharge end of the coal feeding duct, a removable casting covering the hot gas inlet to said second duct and supported by said second duct, and means for connecting the suction side of said fan to the hot gas duct whereby to cause the fan to draw hot gases through the hot gas duct.

5. A stoker of the character described comprising a fuel feeding duct, a fan having its outlet connected to said duct whereby to supply a fluid blast to advance fuel particles through said duct, a fuel inlet to said duct, said duct having means at its outlet end to spread fuel particles laterally as they are blown from the duct, a second duct contiguous to said fuel feeding duct, and having a common heat conducting wall therewith, the second duct having a hot gas inlet at the fuel discharge end of the fuel feeding duct, and means connecting the suction side of said fan to the hot gas duct whereby to cause the fan to draw hot gases through the hot gas duct, and thereby heat the fuel feeding duct.

6. In a stoker having a main frame, a coal feed-

ing casting having one end secured on the frame in position to receive fuel from a hopper or other source, said casting having the other end extending horizontally from the frame a substantial distance for insertion into a furnace, said casting having two ducts therein, one duct having an air inlet and a fuel inlet, the other duct having a hot gas inlet adjacent to the extending end of the first named duct, and a discharge outlet adjacent to the air inlet of the first named duct, a fan, the discharge outlet of the fan being connected to the air inlet of the first named duct, and manually adjustable means for causing the fan to draw more or less hot gases through such second duct for heating the casting.

7. In a stoker having a main frame, a coal feeding casting having one end secured on the frame in position to receive fuel from a hopper or other source, said casting having the other end extending horizontally from the frame a substantial distance for insertion into a furnace, said casting having two ducts therein, one duct having an air inlet and a fuel inlet, the other duct having a hot gas inlet adjacent to the extending end of the first named duct, and a discharge outlet adjacent to the air inlet of the first named duct, a fan, the discharge outlet of the fan being connected to the air inlet of the first named duct, and manually adjustable means for causing the fan to draw more or less hot gases through such second duct for heating the casting, said last named means comprising a conduit forming a part of the discharge outlet of the second duct, and adjustable toward and away from the fan inlet.

GEORGE A. KOHOUT.
